UNITED STATES PATENT OFFICE.

FRANK ENGEL, OF NIAGARA FALLS, NEW YORK, ASSIGNOR TO U. S. LIGHT & HEAT CORPORATION, OF NIAGARA FALLS, NEW YORK, A CORPORATION OF NEW YORK.

POLE STRUCTURE.

1,366,562.

Specification of Letters Patent. Patented Jan. 25, 1921.

Application filed December 13, 1915, Serial No. 68,553. Renewed June 9, 1920. Serial No. 387,778.

To all whom it may concern:

Be it known that I, FRANK ENGEL, a citizen of the United States, residing at Niagara Falls, in the county of Niagara and State of 5 New York, have invented new and useful Improvements in Pole Structures, of which the following is a specification.

This invention relates to pole structures.

More particularly the invention relates to 10 improved means and method of mounting same for preventing the sharp edges on the pole pieces of a dynamo-electric machine from cutting through the insulation of the windings. It has been the practice heretofore to file the edges from the pole pieces, a 15 laborious and therefore expensive operation.

One of the objects of the invention is to provide a pole piece in which danger of cutting through the insulation is obviated.

20 Another object is to provide a simple device which may be applied to the core member of a pole piece to prevent cutting of the insulation.

Another object is to provide an improved 25 method of applying the windings to the pole pieces.

These and other objects are attained by this invention, as will appear from the description which follows.

30 Referring to the accompanying drawings:

Figure 1 is an elevation of a pole piece with a guard and winding.

Fig. 2 is a plan view in section, taken on the line A—A of Fig. 1, the winding being 35 omitted.

The numeral 10 indicates the laminated core of the ordinary pole piece provided with the pole tips 11. Said laminated core is provided with end plates 12 which, as shown in 40 the drawings, are made narrower than the laminated core, so that the laminated core overlaps the end plates on both sides. The pole piece may be secured to the frame 13 in any suitable way.

45 Placed between the windings 14 and the pole pieces are the guards 15, which are

preferably pieces of steel, though other material may be used, of substantially U-shape. These guards are placed on opposite sides of the pole piece with the bottom part of the 50 U arranged against an end plate, as shown in Fig. 2. It will be understood, of course, that the guards should not overlap to form a conductor around the pole piece, as in that case a heavy current would be induced 55 thereon.

The winding 14 is mounted on the pole piece as follows. The formed coil, with the guards 15 lightly held therein, is placed over the pole piece, which, of course, has been 60 removed from the frame 13. Pressure is applied and the guards slip down over the sharp edges of the laminations and the end plates until guards and winding are in their proper position, close to the pole tips. The 65 insulation of the windings is subjected to no rubbing or cutting action, though they are made to fit closely to the pole pieces to prevent shake or distortion during operation of the dynamo-electric machine. 70

One embodiment of the present invention has been described in detail. Many modifications will occur to those skilled in the art without departing from the spirit of the invention as defined in the appended claim. 75

Having described my invention, what I claim as new and desire to secure by Letters Patent of the United States is:—

In combination, a pole piece comprising a laminated core, end plates therefor arranged symmetrically with the laminations of the core but being narrower than said core, whereby recessed corners are provided, a pair of U-shaped guards each embracing three sides of said pole piece, the middle 85 portion of each of said guards being parallel and in contact with an end plate, and a winding encircling said pole piece and guards.

In witness whereof, I have hereunto sub- 90 scribed my name.

FRANK ENGEL.
